No. 861,739.

PATENTED JULY 30, 1907.

A. B. LANDIS.

GRINDING MACHINE.

APPLICATION FILED APR. 7, 1903. RENEWED JUNE 18, 1907.

UNITED STATES PATENT OFFICE.

ABRAHAM B. LANDIS, OF WAYNESBORO, PENNSYLVANIA.

GRINDING-MACHINE.

No. 861,739.

Specification of Letters Patent. Patented July 30, 1907.

Application filed April 7, 1903, Serial No. 151,524. Renewed June 18, 1907. Serial No. 379,606.

To all whom it may concern:

Be it known that I, ABRAHAM B. LANDIS, a citizen of the United States, residing at Waynesboro, in the county of Franklin and State of Pennsylvania, have 5 invented certain new and useful Improvements in Grinding-Machines, of which the following is a specification.

My said invention relates to an improved construction and arrangement of the driving gear for the carriage and the work-holding mechanism of a grinding machine, whereby a single motor mounted upon the machine itself, or any other convenient power, may be employed for driving said carriage and work without the use of overhead shafting, all as will be hereinafter 15 more fully described and claimed.

Referring to the accompanying drawings which are made a part hereof and on which similar reference characters indicate similar parts: Figure 1 is an elevation of one side of a grinding machine embodying my said 20 invention, a portion of the head-stock base and frame being broken away to show the interior construction, and Fig. 2 a detail cross section on the dotted line 2—2 in Fig. 1.

In said drawings the portions marked A represent 25 the main frame of the machine, B the traveling carriage, C the head-stock spindle, and D the motor for driving the gear.

The frame A and traveling carriage B are of substantially the same form and construction as shown in several of my former patents. The grinding wheel W and the mechanism connected therewith are mounted on 30 said carriage B and driven by a motor M also mounted on said carriage. This feature of construction forms the subject matter of a separate application and is 35 therefore not particularly described herein.

The head-stock spindle C is journaled in a sleeve C¹ which is swiveled on the top of a base C² which is mounted to slide upon the top of the table C³.

The motor is an ordinary electric motor of suitable 40 power mounted upon a frame or bracket A² secured rigidly to one end of the frame A of the machine. It is connected by means of a belt 1 with a pulley on the end of a driving shaft 2 which is journaled in suitable bearings in the frame A² beneath said motor. A gear 45 3 is mounted upon said shaft 2 and meshes with a similar gear 4, mounted upon a driving shaft 5 which is also journaled in bearings in frame A² and is the shaft to which is geared the mechanism for driving the traveling carriage B. The gears 3 and 4 are preferably of 50 that character which permits a change of speed between the parts, as shown. Another gear wheel 6 on shaft 2 meshes with a gear 7 on the lower end of a vertical shaft 8, which shaft is mounted in suitable bearings in frame A². Said shaft 8 is provided with a joint 55 9 extending in one direction and a joint 10 extending in the other direction, and between said joints it is

formed in two parts adapted to telescope one within the other, being held from independent rotation by being formed angular in cross section or by a spline and groove connection. Above the joint 10 is mounted 60 another gear wheel, 11, which meshes with a similar gear wheel 12 on the end of a longitudinal shaft 13, which is mounted at one end in a bearing formed in a bracket A³ secured to the end of table C³ and at its other end is mounted in bearings in the base C² of the 65 head-stock, being adapted to slide through said bearings when said head-stock base is adjusted. A small gear wheel 14, is mounted on said shaft 13 just inside of head-stock base and meshes with a gear 15 on the lower end of a vertical shaft 16, which is mounted in 70 bearings in a part connected with the sleeve C¹. Another gear wheel 17 on the same shaft meshes with the gear wheel 18 on a short horizontal shaft 19, mounted in the frame of sleeve C¹ and a gear wheel 20 on the outer end of said shaft 19 engages with internal gear around 75 the flange of the face plate C of the head-stock spindle C. By this arrangement the table C³ on which the head-stock and the foot-stock C⁴ are mounted is permitted to swing on its pivot clamping bolt 25 to any angle desired for the purpose of grinding tapered work 80 or for any purpose, as will be readily understood. The table C³ is clamped to the bed by means of a pivot bolt 25 and washer 26, as indicated, and as shown in several of my former patents, for instance, No. 483,288.

The arrangement of gearing for driving carriage B 85 from shaft 5 may be any arrangement suitable for the purpose, such as shown in some of my former patents, but I have indicated by dotted lines in Fig. 1 a simple arrangement for the purpose of merely showing some operative connection. In the arrangement thus shown, a worm 30 is mounted upon said shaft 5 adapted to mesh with a gear 31 on a transverse shaft 32 which has a pinion 33 meshing with a rack-bar B³ on carriage B. The reversing clutch mechanism commonly used is not shown herein. This arrangement for driving 90 the carriage and the work by a motor carried on the machine itself is very simple and enables the machine to be driven without the use of overhead or line shafting while at the same time providing a machine adapted for universal grinding and to allow the various required speeds for the work and the several adjustments of said work.

It is obvious that a motor need not be mounted upon the machine as shown in drawing but power can be applied to the pulley on shaft 2 from any convenient 105 source without departing from my invention, and still avoid the use of the overhead shafting.

Having thus fully described my said invention, what I claim as new and desire to secure by Letters Patent is:—

1. In a grinding machine, the combination of the frame, a driving shaft thereon, the adjustable table, a head-stock

- and a foot-stock carried thereon, the driven one of which is mounted upon a turning part, a gear connected with the head-stock spindle, flexible gearing connecting said gearing with the driving shaft, a motor, and gearing connecting said motor with said driving shaft, whereby the work may be driven by said motor in different relative positions, substantially as set forth.
2. In a grinding machine, the combination of the frame, the head and foot - stocks, said headstock being mounted on swiveled and sliding parts, gearing connecting the same with the driving shaft, the gearing on said driving shaft being mounted to slide thereon; a motor and gearing connecting the said motor with the said driving shaft, substantially as set forth.
3. In a grinding machine, the combination of the frame, the headstock swiveled upon an adjustable base thereon, a driving shaft extending through bearings in said adjustable base to slide therein, a pinion mounted to slide thereon, gearing connecting said shaft with the rotary center of said headstock, a motor mounted upon the machine, gearing for connecting said motor with the said driving shaft, substantially as set forth.
4. In a grinding machine, the combination of the frame, a table thereon secured to permit of its adjustment, a longitudinally moving carriage, a driving shaft for said carriage, work-holding mechanism mounted upon said table to be adjusted, a motor mounted upon the machine, gearing connecting said motor with the carriage driving shaft, and gearing connecting the same motor with the driving mechanism of the work-holding devices, said gearing embodying universal joints to permit of the adjustment of said mechanism, substantially as set forth.
5. In a grinding machine, the combination of the head-stock spindle mounted in a part pivoted on the base having a face-plate with a gear thereon, a pinion engaging the gear on said face-plate, gearing connected therewith mount-

ed concentric with the pivot point of said pivoted part, and suitable gearing connecting the same with the driving power, substantially as set forth.

6. In a grinding machine, the combination of a head-stock frame mounted on a pivoted table, gearing arranged to drive the face plate, a shaft engaging said gearing running parallel to said table, gearing at the end of said table connected with said shaft, said gearing being connected to the driving mechanism by a telescoping shaft having universal couplings, whereby the pivoted table can be swung into different positions and the driving features not be interfered with, substantially as set forth.

7. In a grinding machine, the combination, of gearing to drive the headstock, a telescopic shaft having universal couplings connected with a shaft on the table and coupled to the driving power, said shaft on the table mounted to allow the headstock to slide into different positions, and the gearing in said headstock structure arranged to allow the headstock spindle to swing at different angles, substantially as set forth.

8. In a grinding machine, the combination of the head-stock mounted upon a pivoted table, gearing connected to its face plate, a longitudinal shaft engaging said gearing and running parallel with said table, the driving power, and a universal extensible connection between said shaft and driving power, whereby said pivoted table can be swung at different angles and be driven, substantially as set forth.

In witness whereof, I, have hereunto set my hand and seal at Waynesboro, Pennsylvania this 2d day of April, A. D. nineteen hundred and three.

ABRAHAM B. LANDIS. [L. S.]
